UNITED STATES PATENT OFFICE.

RICHARD SANDS, OF OSAWATOMIE, KANSAS.

INSULATOR.

1,384,214.

Specification of Letters Patent. Patented July 12, 1921.

Application filed September 18, 1919. Serial No. 324,344.

To all whom it may concern:

Be it known that I, RICHARD SANDS, a citizen of the United States, residing at Osawatomie, in the county of Miami and State of Kansas, have invented certain new and useful Improvements in Insulators, of which the following is a specification.

This invention relates to insulators for electric line wires; and it consists in the novel construction and combination of the parts hereinafter fully described and claimed.

In the drawings, Figure 1 is a side view of an insulator constructed according to this invention. Fig. 2 is a front view, and Fig. 3 is a plan view, of the same. Fig. 4 is a cross-section through the insulating plates, showing them separated.

The frame 2 of the insulator is formed of a block of wood or any suitable molded material or composition. The frame is provided with a stem 3 for attaching it to a crosspiece on a pole or to the limb of a tree. Any other suitable means may however be provided for supporting and securing the frame in position. The frame is provided with a longitudinal chamber 4 which has a semicircular bottom 5, and which is open at each end. A vertical slot 6 is formed at the middle part of the frame and extends longitudinally between the top of the frame and the top of the chamber 4. A screw 7, or other similar clamping device, is provided for contracting the side portions of the frame which are slightly resilient. This screw extends through the slot 6 crosswise of its length.

A cover plate 10 of thin sheet metal, or other suitable material, is provided and is arranged over the top 8 of the frame, and is preferably pivoted to it by a pin 12. The cover plate has a lip or flange 14 which projects over the edge of the frame farthest from the pivot pin 12.

The cover plate prevents the slot from being filled with snow or ice, and the lip holds it in place, but permits it to be sprung upwardly and then moved horizontally upon the flat top of the frame about the pivot pin 12 as a center to expose the slot.

Two blocks 16 and 18 of insulating material are provided. The lower block 16 has

a semicircular bottom 17 which rests on the semicircular bottom 5 of the chamber 4, and the upper block is tapered a little in its thickness so that it forms a key or wedge. The lower block 16 is provided with a longitudinal slot or groove 20 for the line wire 22, and as many grooves as desirable may be provided. The end portions of the upper block 18 are beveled or inclined so as to shed rain water.

The lower block 16 is prevented from sliding out of the rear end of the chamber by means of a stop plate 24 secured to the frame, but any other suitable stop may be provided. The bottom block when placed in the chamber adapts itself to the semicircular bottom thereof. The wire is dropped onto the block 16 through the vertical slot, and the top block 18 is driven in from front to rear to hold the wire in place. The chamber 4 and the insulating blocks are inclined from front to rear to permit rain water to drain away from them. The blocks are finally locked in the chamber by tightening the clamping screw or bolt. The tapering block 18 may be a little narrower than the chamber so that it can easily be driven in to clamp the line wire, and when the screw 7 is tightened the blocks are both locked in place. When the screw is slackened the block 18 can be slid out, and a new or additional line wire can be inserted.

What I claim is:

In an insulator, a supporting frame provided with a chamber extending horizontally through its middle part and having a rounded bottom, said frame having a slot extending from its top to the said chamber, a lower insulating block having a rounded bottom and fitting in the lower part of the said chamber, a tapering upper insulating block normally slideable in the upper part of the said chamber and adapted to clamp the line wire against the lower block, and a clamping device extending through holes in the upper part of the frame and adapted to clamp its upper portion upon the insulating blocks and lock them in place.

In testimony whereof I have affixed my signature.

RICHARD SANDS.
